UNITED STATES PATENT OFFICE.

BARTOLO GAMINO, OF PIGEON, MICHIGAN.

KNEE-PROTECTING DEVICE.

Application filed April 22, 1926. Serial No. 103,729.

This invention relates generally to knee protectors used when working on beet plantations, the invention having more particular reference to a novel type of knee protecting apron.

The invention has for an object the provision of an improved knee protecting apron which will afford greater comfort to the wearer.

10 A further object of the invention is the provision of an improved knee protecting apron which will enable the wearer to maintain a kneeling position for a considerable length of time, without fatigue or injury 15 to the knees of the wearer.

For further comprehension of the invention, and of the objects and advantages thereof, reference will be had to the following description and accompanying drawing, 20 and to the appended claims in which the various novel features of the invention are more particularly set forth.

Fig. 1, of the drawing, illustrates my improved knee protecting aprons applied or 25 attached to the knees of the wearer.

Fig. 2, is a perspective view of my improved knee protecting apron.

Fig. 3, is a transverse sectional view, taken on the line 3—3 of Fig. 2.

30 Fig. 4, is a fragmentary view similar to that shown in Fig. 2, but illustrating a modification of my improved knee protecting apron.

Fig. 5, is a perspective view of a detachable inflatable member, adapted to be used in connection with the modification of my improved device as shown in Fig. 4.

Fig. 6, is a transverse sectional view taken on the line 6—6 of Fig. 4.

40 As here embodied my improved knee protecting apron comprises an inflatable bag 10, or container preferably of rubber, suitably cemented or vulcanized, so as to be air-tight, and provided with a nipple 11, having a removable cap 12. It being understood that the inflatable bag 10 may be inflated with air through the nipple 11 when the cap 12 is removed from the nipple 11, by blowing with the mouth through the nipple 11, or by

45 means of a hand air pump or any similar suitable apparatus.

The inflatable bag 10, is covered, enclosed, or encased in a cover 13, of suitable size and shape to permit the inflatable bag 10 to be 50 inflated. The cover 13 being provided with an aperture 14, to permit the nipple 11 to

extend or project through the cover 13. The cover 13 is provided with side elements 15 and 15', extending therefrom, and having suitably attached thereto, at or near the extremities of the side element 15, depending flexible members 16, or straps, having a plurality of apertures 17, adapted to engage the tongues 18 of the buckles 19, suitably attached at or near the extremities of the side element 15', so as to removably attach or apply my improved device to the knee of the wearer, as clearly shown in Fig. 1 of the accompanying drawing.

The side elements 15 and 15' are provided with notches 20, located adjacent to the lower extremity of the side elements 15 and 15', and at either side of the nipple 11.

Referring in particular to Figs. 3, 4, and 5, of the accompanying drawing, the cover 13 is provided with the ball members 21, of ordinary snap fasteners, located at or near the upper extremity of the cover 13, adapted to removably engage the socket members 22 of the said snap fasteners, suitably attached to the cover 23.

The inflatable bag 24, or container, preferably of rubber, and construction similar to the above mentioned inflatable bag 10, and provided with a nipple 11 and removable cap 12, is covered, encased or enclosed in the said cover 23 which preferably comprises a rigid flat upper member 23'.

The latter described construction is such as will permit the cover 23 to be attached to the cover 13, so as to provide a table, which may be used for pounding or hammering upon, so as not to injure the knee of the wearer.

Having thus described my invention, what I claim as new and desire to protect by Letters Patent of the United States is as follows:

1. A knee pad comprising an inflatable bag of oval cross section, a cover enclosing said bag, and an inflatable member adapted to be detachably secured to said pad comprising a flat rigid upper surface adapted to provide a supporting platform on the knee of the wearer.

2. A knee pad comprising an inflatable bag of oval cross section, an outer casing enclosing said bag, a supporting member having a concaved bottom adapted to fit the curvature of said pad and an upper flat rigid surface adapted to provide a platform, and fastening means on said outer

casing for detachably securing said supporting member to said bag; said fastening means being positioned at the upper end of said casing for attaching said supporting means to the position of the pad immediately above the knee of the wearer to provide a supporting platform adapted to assume a substantially horizontal position when the wearer is seated.

10 3. The combination with a pneumatic knee pad, of a pneumatic supporting means

comprising a flat rigid upper surface adapted to be attached to said pad above the knee portion thereof, and means for detachably securing said supporting means to said pad, 15 said supporting means being adapted to assume a substantially horizontal position on the leg of the wearer when the wearer is seated.

In testimony whereof I have affixed my 20 signature.

BARTOLO GAMINO.
